UNITED STATES PATENT OFFICE.

WARREN DELAWARE AMBROSE, OF NACOGDOCHES, TEXAS.

LIQUID-VENDING MACHINE.

Application filed December 13, 1923. Serial No. 680,555.

To all whom it may concern:

Be it known that I, WARREN D. AMBROSE, a citizen of the United States, and a resident of Nacogdoches, in the county of Nacogdoches and State of Texas, have invented a new and Improved Liquid-Vending Machine, of which the following is a full, clear, and exact description.

This invention relates to improvements in vending machines and has particular reference to a coin-control mechanism for liquid vending machines.

An object of the invention is to provide an improved mechanism capable of operation with a pump such as used to dispense gasoline, oil and other liquids in predetermined quantities and which is controlled in such manner that a coin deposited into the mechanism is utilized to release an operating element forming a part of the pump so that said element may be actuated to dispense a predetermined quantity of liquid from said pump.

The above and other objects will appear more clearly from the following detail description, when taken in connection with the accompanying drawing, which illustrates a preferred embodiment of the inventive idea.

39 In the drawing—

Figure 1 is a side elevation of the coin-control mechanism constructed in accordance with the invention and showing the same applied to a reciprocatory pump rod; Figure 2 is a section substantially on the line 2—2 of Figure 1; and

Figures 3, 4 and 5 are detail views showing the various relative positions of the operating shaft for the pump and the latching means therefor during the rotation of said shaft.

Referring more particularly to the accompanying drawing, the numeral 6 indicates a frame the lower ends of which are secured in any preferred manner to a pump structure (not shown), the operation of which is controlled by a vertically reciprocating pump rod 7, in the form of a rack bar, having its upper end slidable in a suitable bearing formed in the cross-piece 8 of the frame 6, the upward movement of the rod 7 being utilized, as usual, to dispense the liquid from a suitable tank by the action of the pump. Suitably journaled in the side members of the frame 6 is a rotatable operating shaft 9 having a handle 10 at one end

and a gear 11 carried intermediate its ends which is engageable with the rack of the pump rod to raise and lower the same when the shaft 9 is rotated. The shaft 9 may be 60 motor driven, if desired.

Depending from the cross-piece 8 of the frame 6 is a coin chute 12 forming a part of the coin-control mechanism, which chute is arranged directly above an intermediate 65 portion of the shaft 9 having a slot 13 extending transversely therethrough.

The ends of the slot 13 are diagonally arranged so that one longitudinal edge of the slot is of greater length than the other, 70 as indicated in dotted lines in Figure 1, the latter edge of said slot being of slightly less length than the diameter of a coin to be deposited into the mechanism so that a portion of said coin, when in operative position, will project beyond the shaft 9. Said shaft is normally held against rotation in one direction by means of a latching member 14 pivoted at one end, at 15, with the lower end of an angular supporting member 16, the opposite end of which is connected to the cross-piece 8 of the frame 6. The end 17 of the latch 14 is bent laterally to form a hook portion the free extremity 75 of which is engageable in a notch 18 formed in the periphery of the shaft 9 adjacent the slot 13 therein and when thus engaged in said notch the latching member will prevent rotation of the shaft 9 in a clockwise direction, as viewed in Figure 2, but will permit of rotation of said shaft in the opposite direction so that the pump rod 7 may be lowered to its normal position after having been elevated to dispense a quantity of liquid. A leaf spring 19 having one end 80 secured to the support 16 is utilized to yieldably maintain the latching extremity of the latch 14 in engagement with the shaft 9.

With the parts in the position shown in Figure 2, the coin 20 is inserted into the upper end of the chute 12 and is directed thereby into the longer edge of the slot 13 in the shaft 9. The coin passes through the slot until the same engages the ends of the shorter edge thereof, at which time a portion of said coin projects beyond the shaft 9. The handle 10 may then be rotated in a clockwise direction, as viewed in Figure 2, to rotate the shaft 9. A slight rotation of said shaft causes the coin 20 to engage 100 the latch 14, as shown in Figure 3, thus swinging said latch upwardly about its 105 110

5 pivot 15 so that continued rotation of the shaft will carry the notch 18 therein beyond the latching extremity of said latch. As the shaft reaches the position shown in Figure 4, pressure of the spring 19 against the latch will again force said latch toward its normal position and this movement is utilized to eject the coin 20 from the slot 13 which has now reached an inclined position with respect to the horizontal with the longer edge of the slot in a plane below that of the other edge thereof, thus permitting the disengagement of the coin from the shaft. As the coin is ejected from the 10 shaft the same falls into a coin box 21 carried by the frame 6.

15 A clutch device is associated with the shaft 9 and includes a clutch member 22 carried by the gear 11 and a second clutch member 23 cooperating with the clutch member 22 and mounted for longitudinal movement upon the shaft 9. The clutch member 23 is provided with a diagonally extending slot 24 into which projects a pin 25 carried by the shaft 9 so that as the shaft is rotated in the proper direction the pin 25 will cause a longitudinal movement of the clutch member 23 into cooperative relation with the member 22, thus providing a positive drive between the shaft 9 and gear 11 to elevate the pump rod 7. When the shaft 9 has made substantially a complete revolution the free end of the latch 14 will engage in the notch 18 of the shaft and thus prevent any further rotary movement of the latter. The pump mechanism may be so regulated that upon a complete revolution of the shaft 9 the proper quantity of liquid will be dispensed from the pump. The 20 clutch member 23 is mounted for rotation on the shaft 9 between the upper free ends of a bracket 26 secured to the frame 6 hav-

ing an inner lining 27 of leather or other suitable material.

25 After the pump rod 7 has been elevated to the limit of its upward movement by the operation of the shaft 9 the handle 10 may be rotated in an opposite direction to lower the rod 7. When moving in the latter direction the clutch member 23 will restore to its normal position out of cooperative relation with the member 22. The rotation of the handle in said opposite direction may be continued until the rod 7 has been lowered to its normal position whereupon the 30 parts are in position for another operation. Should the slot 13 for any reason fail to register exactly with the lower end of the chute 12 when a coin is deposited into said chute, it is obvious that a slight movement of said shaft will cause said slot to register 35 with the chute so that the coin will drop into proper position in engagement with said shaft.

40 What is claimed is:

45 In a coin controlled mechanism, a reciprocating element, a shaft having a slot for holding a coin partly projecting therethrough and notch adjacent the slot, means for operating the element from the shaft, 50 means for feeding a coin into the slot of the shaft, and a pivoted and spring pressed member having at its free end a hook extending over the shaft and having its extremity engaging the notch of the shaft to 55 prevent it from turning in one direction but permitting it to turn in the other direction, the said member engaging the portion of the coin projecting through said slot, upon the 60 rotation of the shaft to first disengage its hook from the notch of the shaft and then to be expelled thereby from the slot.
